UNITED STATES PATENT OFFICE.

MICHAEL TEEHAN, OF NEW YORK, N. Y.

BEER OR ALE PIPE CLEANER.

SPECIFICATION forming part of Letters Patent No. 609,635, dated August 23, 1898.

Application filed November 21, 1896. Serial No. 612,941. (No model.)

To all whom it may concern:

Be it known that I, MICHAEL TEEHAN, a citizen of the United States of America, and a resident of New York, (Brooklyn,) in the county of Kings and State of New York, have invented certain new and useful Improvements in Beer or Ale Pipe Cleaners, of which the following is a specification.

My invention has reference to improvements in beer and ale pipe cleaners, and has for its objects, first, to insure the passage of the flushing charge through the pipes to be cleaned without appreciable dilution by the flushing-water employed to force it through the same; secondly, to enable a predetermined quantity of flushing liquid to be forced through the pipes, and, thirdly, to present the cleaner in a compact form for ready and easy attachment, so that the cleaning process can be rapidly carried out.

In one form of apparatus employed for flushing beer and ale pipes a reservoir of considerably larger area than that of the beer or ale pipe and that of the water-supply pipe is used. In such devices the water naturally is forced into and through the body of the flushing charge and mixes therewith, leaving uncertain the actual strength of the solution passing through the pipes. In another form the water is passed through a reservoir containing the granulated material, and therefore it is difficult to predetermine the strength of the solution. To overcome these difficulties, I form a reservoir for the flushing solution, preferably in coil form and having an area of cross-section substantially equal to that of the beer or ale pipe and opening with its full area to the flushing-water supply, said reservoir being provided with suitable means for its attachment to the beer, ale, and water pipes.

The nature of my said invention will best be understood when described in connection with the accompanying drawings, in which—
45 Figure 1 represents a side elevation, on a reduced scale, of a cleaner constructed according to my invention. Fig. 2 is a similar view showing the cleaner placed in its operative position.

50 Similar letters and numerals of reference

designate corresponding parts throughout both views of the drawings.

Referring to the drawings, the letter A designates the reseservoir for the flushing solution, made of tubing, preferably beer-pipe, 55 wound substantially into a tapered helical coil. The discharge end 1 of the tubing is located at the upper end of the coil, and the inlet end 2 is extended upwardly from the bottom of the coil, through the inside of the 60 coil, and turned over to form a bend 6. The discharge end 1 of the coil is provided with a coupling end 3 for its attachment, by means of a coupling-union 4, to the end of the rubber hose 5 usually placed in permanent connection with the end of the beer or ale pipe B. The inlet end 2 is provided with a coupling 7 for the attachment of the usual cock 8, to which can be attached a flexible hose W, placed in connection with the hydrant or other 70 source of supply for the flushing-water.

As before stated, the coil has an area of cross-section equal to that of the beer or ale pipes, and consequently it has less area of cross-section than the ordinary hydrant-pipe 75 and opens with its full area to the flushing-water supply. If, therefore, the supply of water is turned on, the solution in the reservoir must necessarily be bodily forced out of the same and through the beer or ale pipes 80 without the water appreciably intermixing therewith, and consequently said solution retains its original strength.

To clean the pipes, the reservoir, which is constructed to hold about a pint of flushing 85 solution, is filled with the solution through the end 1. The construction herein described permits the coil to be filled without closing off a cock. The reservoir is then attached to the hose 5 by means of the coupling 4 and to 90 the water-supply hose W. The hydrant-water is then turned on. It will be readily understood that this operation can be quickly carried out and that the complications usually involved in making the change are avoided. 95

It is of course to be understood that the reservoir could be coiled into a spiral or other suitable form, the object of coiling the same being merely to present it in a more compact form.

While I have herein described the tubing from which the reservoir is made as having substantially the same area of cross-section as the beer or ale pipes, it must of course be understood that it could be slightly larger or smaller in area. It must also be understood that the area of cross-section of the reservoir-tubing could be somewhat larger or smaller than the area of cross-section of the water-supply; but such area of tubing should not be large enough in any instance to permit intermixing of flushing solution and water.

What I claim as new is—

1. As a new article of manufacture, a beer or ale pipe cleaner made of tubing wound in coil form and having one end turned upwardly from its top and its other end turned upwardly from its bottom and extended through the coil, combined with means for the attachment 20 of said coil, substantially as described.

2. A beer or ale pipe cleaner consisting of a coiled, tubular reservoir of substantially constant area of cross-section throughout, adapted to receive and contain a flushing solution and provided with inlet and discharge ends both located at the top of said reservoir, and means for connecting the inlet end of the reservoir substantially with its full opening

to the flushing-water supply, substantially as described.

3. A beer or ale pipe cleaner made of tubing wound in coil form and having an upwardly-turned discharge end, and an inlet end turned upwardly from the bottom of the coil and extending through the same, combined with means for the attachment of said coil, substantially as described.

4. In an apparatus for cleaning beer or ale pipes, the combination of a reservoir adapted to be filled with a flushing liquid; said reservoir being formed of a coiled pipe of substantially the diameter of the pipe to be cleaned and having both ends located above its top; a flexible hose connected to a water-supply; and couplings for connecting the ends of the 45 coiled pipe respectively to the hose leading to the water-supply and to the pipe to be cleaned, substantially as described.

In testimony that I claim the foregoing as my invention I have signed my name, in presence of two witnesses, this 19th day of November, 1896.

MICHAEL TEEHAN.
